SILENT ANTISIPHON FIXTURE

George J. Morris, Los Angeles, Calif.

Application February 14, 1940, Serial No. 318,847

4 Claims. (Cl. 137—111)

This invention relates generally to plumbing installations, and more particularly to the control of water from a source of supply to various fixtures by means preventing back-siphoning of water with the attending danger of contaminating fresh water in the system, and enabling water to be delivered in comparative silence to flush tanks of toilets.

An object of this invention is to provide means of extremely simple construction eliminating moving parts, by which back-siphoning of water from a fixture into the fresh water supply of the system will be positively prevented, and which, in its association with a ball cock, controls the flow of water into the tank in a manner to eliminate objectionable water noises.

With this and other objects in view, the invention resides in the combinations, arrangements and functional relationships of elements as set forth in the following specification and particularly pointed out in the appended claims.

In the accompanying drawing:

Figure 1 is a vertical sectional view illustrating the invention installed in a flush tank;

Figure 2 is a vertical sectional view taken on the line 2—2 of Figure 1;

Figures 3 and 4 are horizontal sectional views taken, respectively, on the lines 3—3 and 4—4 of Figure 2, and looking in the directions of the respective arrows.

In its present embodiment, the invention comprises a ball cock C for a flush tank T, and is composed of a body 10 having a cylindrical bore 11 opening at one end into a chamber 12 having a lateral outlet 13 and an axial inlet 14 defined by the annular seat 15 of a cap 16 threaded at 17 into one end of the body.

The cap 16 forms part of an elbow fitting 18 into which is screwed an inlet pipe 19 extending through a suitably sealed opening in the bottom wall of the tank T and connected to a source of water supply under pressure, such as is available for domestic purposes. The pipe 19 rigidly supports the body 10 in a horizontal position above the highest water level in the tank T and with a lateral extension 12a of the chamber 12 which is provided with the outlet 13, disposed above the chamber, for a purpose to be later described.

Co-acting with the seat 15 is a cylindrical valve plunger 20 slidably mounted in the bore 11 and provided at its inner end with a sealing washer 21 adapted to engage the seat 15 to seal the inlet 14. The plunger 20 is also provided with

a peripheral sealing ring 22 to prevent leakage of water between the plunger and the body 10.

An actuating mechanism for the plunger 20 comprises an L-shaped lever 23, one end of which is pivotally mounted at 24 on a bifurcated arm 25 depending from the body 10. From the other end of the lever 23 extends a float rod 26 to the free end of which is fixed the usual float (not shown).

Intermediate its ends there is pivoted at 27 to the lever 23, one end of a pair of links 28, the other end of which is pivotally connected at 29 to one end of a lever 30 pivotally mounted intermediate its ends at 31 on the arm 25 so as to extend freely through the bifurcated portion thereof.

The other end of the lever 30 extends freely through a diametric slot 32 in an extension 33 on the plunger 20, and is provided with a cam surface 34 adapted to co-act with an abutment 35 formed by the outer end wall of the slot 32 to effect opening movement of the plunger substantially axially and rectilinearly with respect to the bore 11. Said other end of the lever is also provided with a threaded bore in which is threaded for adjustment a screw 36 having a conical end 37 seating freely in a conical socket 38 formed in the outer end of the plunger in coaxial relationship thereto, and co-acting with the plunger to effect closing movement thereof substantially axially and rectilinearly with respect to the bore 11. A stop projection 39 on the arm 25 co-acts with the lever 30 to limit the opening movement of the plunger 20, and hence the lowered position of the float, irrespective of emptying of the tank T.

The upper end of a filling tube 40 is connected by an elbow fitting 41 to one end of a reducing coupling 42, the other end of which is threaded into the outlet 13 so as to rigidly support the tube 40 to depend vertically in the tank with the lower end of the tube spaced a short distance from the tank bottom.

At a point considerably above the water level in the tank T, the wall of the tube 40 is provided at two diametrically opposed points with slots 43 to provide an air gap or vacuum breaker at this location in the tube. Fixed in the tube at approximately the upper end of the slots 43 is a water confining and directing element E in the form of a rectangular strip of relatively thin gage metal corrugated transversely and bent into circular form to snugly fit into the tube 40 for co-action therewith in defining a number of parallel and axially extending water passages 44 in

the tube which function to confine the water against spreading when traversing the slots 43, so that the water will be maintained in a solid column at this point and will be prevented from discharging through the slots, as well as picking up air with the attending objectionable noise.

In the use of the invention in a flush tank or similar installation in which water noises are to be avoided as much as possible, a second element E' identical to the element E is fixed in the tube 40 at approximately the lower end of the slots 43 as an aid in further reducing water noises. However, this second element has a tendency to create a slight back pressure with the possible spilling of a small quantity of water through the slots 43, and in order to provide for this contingency, a sleeve 45 is fitted tightly on the tube 40 and has an upper flaring portion 45a surrounding the lower portions of the slots 43 so as to act as a collector for any water which might discharge through the slots, and to divert such water back into the tube and/or through ports 45b in said flaring portion 45a so that excess water will flow down the outside of the tube.

At a location just above the slots 43, a baffle member 46 of inverted cup shape is fixed on the tube, so that in the event that water should be delivered to the tube at a pressure in excess of a predetermined maximum pressure, and strikes the element E' with sufficient force to be deflected upwardly, the water will impinge against the baffle member so as to be prevented from striking the top of the tank and possibly leaking therefrom.

To muffle the noise of water issuing from the bottom of the tube 40, a third element E2 also identical in construction to the element E, can be installed in the tube as shown.

The operation of the invention is as follows:

With the invention installed in a plumbing system, it will be clear that should the float controlled valve plunger 20 fail to seal the inlet 14 when the tank T has been filled to the highest level possible as determined by an overflow tube (not shown), and that should a suction be created in the water supply line at such time, the vacuum breaker provided by the slots 43 will prevent the siphoning of water from the tank, and instead will merely suck air, thus positively preventing contamination or pollution of fresh water in the supply line all without the necessity for any moving parts and yet preventing objectionable noises at the slots 43 during the filling operation, by the functioning of the element E in maintaining a solid water column in the tube at the slots.

Furthermore, it will be noted that by virtue of the horizontal position of the body 10 and the lateral extension 12a of the chamber 12 to the outlet 13 being disposed above the noise creating restriction between the seat and the plunger which is intensified during the final closing movement of the plunger, a body of water fills the chamber and lateral extension thereof at all times during the filling operation, so as to constantly submerge the seat 15 and co-acting end of the plunger 20, thus effectively muffling this objectionable water noise.

It will also be noted that by the provision of the motion transmitting screw 36 and conical socket 37, the arcuate motion of the lever 30 in tending to tilt the plunger 20 is compensated for, so that the lever motion is resolved into a substantially rectilinear motion at the plunger.

This effect is also obtained during opening movement of the plunger by the cam 34 which co-acts with the abutment 35 in wiping across the latter laterally of the plunger axis during arcuate motion of the lever, thus tending to apply force to the plunger parallel to its axis, irrespective of the arcuate motion of the lever.

The tendency to tilt or rock the plunger 20 in its bore 11 is thus negligible, so that excessive wear on the plunger and/or the bore 11 as well as premature failure of the sealing gasket 22 are prevented. Furthermore, the parallel relationship which is maintained between the face of the washer 21 and the annular seat 15 by virtue of the rectilinear movement imparted to the plunger 20 obviates such water noises at the inlet 14 as would occur in the event that the washer was inclined with respect to the seat 15 sufficiently to cause considerable more restriction to the flow of water past one portion of the seat than another during final closing movement of the plunger.

What is claimed is:

1. In a flush tank ball cock having a water inlet from a source of pressure supply and water outlet, a vertically disposed filling tube connected to the outlet; means defining an opening in the tube adapted to be positioned above the high water level in a tank, through which air will be drawn into the tube should back-siphoning occur through the ball cock; two means respectively defining a plurality of water passages in the tube parallel to its axis and in juxtaposition to the top and bottom of the opening, the top one of said two means operating to confine the water in the tube against discharging through said opening, and the bottom one of said two means aiding the first one thereof in obviating air noises at the opening; and means co-acting with the opening for collecting and returning to the tube any water which discharges through the opening upon striking the bottom one of said two means.

2. In a flush tank ball cock having a water inlet from a source of pressure supply and a water outlet, a vertically disposed filling tube connected to the outlet; means defining an opening in the tube adapted to be positioned above the high water level in a tank, through which air will be drawn into the tube should back-siphoning occur through the ball cock; two means respectively defining a plurality of water passages in the tube parallel to its axis and in juxtaposition to the top and bottom of the opening, the top one of said means operating to confine the water in the tube against discharging through said opening, and the bottom one of said two means aiding the first one thereof in obviating air noises at the opening; and means defining an annular well around the tube opposite the opening, for collecting and returning to the tube, water which might discharge through the opening upon striking the bottom one of said two means.

3. In a flush tank ball cock having a water inlet from a source of pressure supply and a water outlet, a vertically disposed filling tube connected to the outlet; means defining an opening in the tube adapted to be positioned above the high water level in a tank, through which air will be drawn into the tube should back-siphoning occur through the ball cock; two means respectively defining a plurality of water passages in the tube parallel to its axis and in juxtaposition to the top and bottom of the opening.

ing, the top one of said two means operating to confine the water in the tube against discharging through said opening, and the bottom one of said two means aiding the first one thereof in obviating air noises at the opening; means co-acting with the opening for collecting and returning to the tube any water which discharges through the opening upon striking the bottom one of said two means; and a baffle member surrounding the tube above the opening, against which will impinge water deflected upwardly upon striking the second one of said two means as a result of the water being delivered to the tube at a pressure in excess of a predetermined maximum pressure.

4. In a flush tank ball cock having a water inlet from a source of pressure supply and a water outlet, a vertically disposed filling tube connected to the outlet; means defining an open-

ing in the tube adapted to be positioned above the high water level in a tank, through which air will be drawn into the tube should backsiphoning occur through the ball cock; two means 5 respectively defining a plurality of water passages in the tube parallel to its axis and in juxtaposition to the top and bottom of the opening, the top one of said means operating to confine the water in the tube against discharging through said opening, and the bottom one of said two means aiding the first one thereof in obviating air noises at the opening; and means defining an annular wall around the tube opposite the opening, for collecting water which might discharge 10 through the opening upon impinging against the lower one of said two means; the last means having ports through which collected water can drain to flow down the outside of the tube.

GEORGE J. MORRIS.
